UNITED STATES PATENT OFFICE.

GASTON A. GUYOT, OF ATTLEBORO, MASSACHUSETTS, ASSIGNOR TO GUYOT BROTHERS COMPANY INC., OF ATTLEBORO, MASSACHUSETTS.

ORNAMENTAL SHOE-BUTTON COVER.

Application filed June 1, 1927. Serial No. 195,852.

This invention relates to certain new and useful improvements in ornamental shoe button covers, and the primary object of the invention is to provide a shoe button cover 5 wherein the entire structure is formed without the use of solder, thereby to permit the employment of celluloid, cloth or other inflammable material, as a decorative element.

The invention further aims to provide a 10 shoe button cover which is of simple construction and of greatly increased strength, so as to prevent accidental disengagement of the anchoring device or bridge which engages the shoe button.

15 In the drawings:—

Figure 1 is top plan view of the invention;

Figure 2 is bottom plan view, and

Figure 3 is a section on line 3—3 of Figure 1.

In proceeding in accordance with the present invention a metal front 1 which may be of any desired configuration, but here shown as circular, is employed and is provided 20 with cut-outs 2 which form any desired design or ornamentation. A celluloid, cloth or other member 3 is superimposed on the front 1 and has in turn a backing 4 which may be of metal superimposed thereon as shown in Figure 2. The marginal edge of the backing plate 5 is bent outwardly at an angle toward the front 1 and over the marginal edge of the celluloid or cloth member 3. The attaching means for the cover is 25 composed of metal ring 6 having its marginal edge flanged outwardly at 7 and engaged with the inclined marginal edge 5 of the metal back 4. A bridge 7 having a U-slot 8 is formed integral with the ring 6 and extends diametrically thereacross. The 30 slit 8 engages the shank of the shoe button. With the parts thus engaged the marginal edge of the metal front 1 is rolled inwardly to overlie the ring 6 and to hold the latter 35 in position.

By inclining the margin of the back 4 the latter is strengthened and the celluloid or

cloth member 3 more firmly secured in place. Similarly by flanging the ring 6 at 7 the 50 ring is strengthened and in addition a biting edge is provided which engages the inclined margin 5 so as to provide a thick solid and substantial marginal peripheral portion for the entire button as is evident in Figure 3.

Having thus described my invention what I claim as new and desire to secure by Letters Patent is:—

1. In an ornamental shoe button cover, a metal front having cut-out portions, a colored celluloid member engaged with the front so as to be visible through the cutout portions, a backing member superimposed on the celluloid member and having its marginal edge extending over the marginal edge 60 of the celluloid member and at an incline toward the front, a ring-like member having its marginal edge flanged toward the front and engaged with the inclined edge of the 65 backing member, and a shoe button-engaging part on the ring-like member, the marginal edge of each front being rolled over the marginal edges of the celluloid member, the backing and the ring-like member and onto the latter.

2. In an ornamental shoe button cover, a metal front having cut-out portions, a colored celluloid member engaged with the front so as to be visible through the cutout portions, a backing member superimposed on the celluloid member and having its marginal edge flush with the marginal edge of the celluloid member, a ring-like member engaged with the backing member and having its marginal edge flush with the 70 marginal edge of the backing member, and a shoe button-engaging part on the ring-like member, the marginal edge of the front being rolled over the marginal edges of the celluloid member, the backing and ring-like 75 member and onto the latter.

In testimony whereof I have signed my name to this specification.

GASTON A. GUYOT.
